HAMMER MILL

Ralph L. Sherman, Downers Grove, Ill., assignor
to The Myers-Sherman Company, Chicago, Ill.,
a corporation of Ohio

Application October 3, 1932, Serial No. 635,981

5 Claims. (Cl. 83—11)

This invention relates to hammer mills in general and particularly to a chute or trough into which materials to be ground by the hammer mill machine are fed to proper position.

5 The primary object of the invention is to provide a new and improved removably and adjustably mounted chute for hammer mills.

A further object is to provide a hammer mill 10 which has an opening at the upper part thereof, one side of the opening being defined by an arcuate portion of the casing; which has a chute or trough supported by said arcuate portion and adjustably connected to said arcuate portion whereby the opening may be increased or diminished 15 depending upon the kind of material fed into the machine.

A further object of the invention is to provide a hammer mill which has a feed opening arranged in a particular position; which has a chute adjustably mounted for the purpose of causing the material fed into the hammer mill to be deposited in a particular position relative to the hammer mill mechanism, and which is provided with means whereby the chute may be arranged in various positions to vary the size of the opening depending upon the kind of material fed into the machine.

Numerous other objects and advantages will be apparent throughout the progress of the following specification.

The accompanying drawing illustrates a selected embodiment of the invention and the views therein are as follows:

Fig. 1 is a detail perspective view of a hammer mill having the improved removable and adjustably mounted chute or trough mounted thereon.

Fig. 2 is a detail sectional view on the line 2—2 of Fig. 1.

Fig. 3 is a detail sectional view on the line 3—3 of Fig. 2.

The hammer mill comprises a transverse shaft 5 which is supported in bearings or journals 6 operatively fixed to the hammer mill casing 7. A pulley 8 is fixed to one end of the shaft and has a belt or other member 9 wrapped therearound and driven by a prime mover, such as a gasoline motor. A plurality of spaced circular members 10 are arranged inside of the casing 7 and carry a plurality of circumferentially arranged pivotally mounted hammers 11.

A fan or blower 12 is operatively connected to the opposite end of the shaft 5 and is driven by said shaft. The fan or blower is encased in a casing 13, and a pipe 14 is operatively connected 5 to the casing 13 and leads to a hopper 15 of the cyclone type. The front part of the casing 7 is curved as indicated at 16 and extends inwardly to a point designated at 17. The edge 17 of the front part of the casing is spaced from the upper 0 edge 18 of the curved rear face 19 of the casing.

The space between the point 17 and the edge 18 forms an opening 20 which, for the purpose of convenience, will be termed the feed opening as it is through this opening that the material to be ground, chopped or pulverized is fed into position into the machine. The material which passes into the opening 20 is ground or chopped up by the centrifugal action of the hammers 11 which material, when ground or chopped up, falls through the bottom 21 and is deposited into the receptacle 22 where it is deposited in the hopper 15, there being a member 23 operatively connected to the receptacle 22 and the fan 12. A chute or trough 24 is provided for feeding material into the hammer mill. This chute comprises a relatively U-shaped feed portion 25 having an apron 26 connected thereto, the chute being graduated in size, being relatively low at the far end as indicated at 27 and being relatively high at its inner end as designated at 28. The inner end of the chute has an arcuate depending portion 29, Fig. 2, which is pivoted to the end of the chute as indicated at 30. This arcuate member is formed to conform with the arcuate shape of the curved portion 16 of the casing and is adapted to slide 25 on said curved portion for the purpose of adjusting the chute relative to the hammer mill. The arcuate portion 29 is provided with spaced cross ribs 31 which are struck from the sheet metal portion 29. A roller 32 is revolvably supported in 30 the side portions of the frame 7 and engages the upper or outer face of the member 29 to hold this latter member against the curve portion 16. This roller is arranged between the ribs 31 and limits the slidable movement of the member 29 35 when the roller is engaged by the ribs. The purpose of adjustably mounting the chute is to vary the size of the feed opening 20. When the chute is in the position shown in solid lines in Fig. 2, the opening 20 is relatively large, but when it is 40 moved to the position indicated in dotted lines, the size of the opening will be materially reduced. Another reason for making this chute adjustable is to permit the chute to be inclined, if desired. The chute is supported by a pair of bars 33 which 45 carry a pivot pin 34 at their upper ends, the pivot pin 34 operating in a slot 35 provided in a member 36 which is fixed to the chute. The rods or supports 33 are pivotally supported by a cross member or rod 37 which is revolvably supported by 50 the members 38 and 38' fixed to the casing 7.

A feed shutter 39 may be suitably mounted so that it will extend inside of the chute. This member 39 comprises a face 40 having an opening 41 through which the material being fed 55 to the hammer mill passes. Arms 42 are fixed to the member 40 and are pivotally supported on a cross rod 43, Fig. 2. In order to vary the size of the opening 41, a slidable plate 44 is provided. This plate is provided with a slot 45 60

through which a pin 46 mounted on the member 40 extends, a thumb nut 47 being provided on the member 46 for holding the plate in position.

5 A fly 48 is pivotally supported on the rod 43 for the purpose of preventing any meal or dust from passing through the opening 20.

The purpose of making the chute adjustable is to not only vary the size of the opening 20 but 10 to feed the material to a predetermined position relative to the axial center line of the hammer mill itself, it being preferable in some instances to feed the material slightly to the right side, Fig. 2, of the shaft 5 and sometimes to

15 the left side of the shaft 5 depending upon the material to be acted upon. When materials like corn, oats, and other grain are fed into the hammer mill, it is desirable to reduce the sizes of the openings 20 and 41 so that too much ma-

20 terial is not fed into the hammer mill at one time. When more bulky material, such as hay, is fed into the machine, it is desirable that the openings 20 and 41 be as large as possible. If

25 an opening larger than the full size of the opening 41 is required, the entire plate 40 and its co-operating parts may be removed. Also, it may be desirable to feed bulky material, such as hay, into a different position relative to the center line of the hammer mill. Thus, by making the chute 30 adjustable relative to the feed opening and providing an adjustable opening within the confines of the chute, materials of various kinds ranging from the finer grains to bulky material, such as hay, may be acted upon with facility.

35 The plate 29, as previously mentioned, is slidably mounted on the face 16 of the casing and the plate 29, along with the chute 24, is moved upwardly and downwardly relative to the arcuate face 16 so as to vary the size of the opening 20.

40 This slidable movement of the plate 29 and the chute 24 is accomplished by mechanism 50 which comprises a clevis-shaped member 51 having spaced legs 52, the member 51 being provided with a central opening through which the rod

45 51 passes and is maintained in fixed position on this rod by means of a set screw 53. A link 54 extends between the spaced legs 52 and is pivotally connected thereto, as indicated at 55, Fig. 2. The upper end of the link 54 is pivoted at 56 50 to a pair of spaced angle members 57. The spaced angle members 57 are welded or otherwise fixed to the plate or arcuate depending portion 29.

An operating handle 58 is fixed to the rod 37 55 for the purpose of operating the mechanism 50. When it is desired to move the plate 29 and the chute 24 to vary the size of the opening 20, the handle 58 is operated. The handle 58 being fixed to the rod 37, will rotate or oscillate this 60 rod depending upon the movement of the handle 58. When the rod 37 is rotatively moved, the member 51 will likewise move, pulling on the link 54 which is attached to the plate or member 29, thereby moving the plate 29 upwardly 65 and downwardly along the arcuate surface 16 to vary the size of the opening 20. The movement of the depending portion or member 29 is limited by the cross member 32 as, when the device is in the position shown in full lines in Fig. 1, the 70 roller 32 will be against the cross rib 31. When the handle is raised to move the member 29 to the position indicated in dotted lines in Fig. 2, the protuberance or cross rib 31 will be in en-

gagement with the rod or roller 32. The cross bar or roller 32 is preferably removably supported in position so that after its removal, the plate or depending portion 29 may be removed merely by disconnecting the link 54 from either the member 51 or the supporting angles 57.

The invention provides a hammer mill having a chute support adjustable relative to the hammer mill to cause the materials to be fed into the hammer mill at a predetermined position and to feed a predetermined amount of material.

The chute is also adjustable to vary the angle of inclination, as desired.

Changes may be made in the form, construction, and arrangement of the parts without departing from the spirit of the invention or sacrificing any of its advantages, and the right is hereby reserved to make all such changes as fairly fall within the scope of the following claims.

The invention is hereby claimed as follows:

1. A hammer mill comprising a casing having a feed opening therein, an arcuate member conforming with the shape of a part of said casing and slidably positioned thereon to vary the size of the feed opening depending upon the position of the member relative to the opening, a chute pivotally connected to said member, means pivotally connected to said member and to a part of said casing for moving said member and said chute relative to the opening, said means comprising a cross bar fixed to the casing, a handle fixed to the cross bar, and linkage connecting the cross bar and the member whereby rotative movement of the cross bar upon moving the handle will cause slidable movement of the arcuate member relative to the arcuate casing.

2. A hammer mill comprising a casing having a feed opening therein, a member slidably fastened to said casing adjacent the opening to vary the size of said opening, a chute pivotally connected to said member, and means for shifting said chute to move said member and thereby vary the size of said feed opening.

3. A hammer mill comprising a casing having a feed opening therein, a chute arranged in position to feed into said opening, said chute having a member fastened thereto slidably engaging the casing adjacent the feed opening whereby adjustment of the chute will move the member in respect to the opening and vary the size of the feed opening.

4. A hammer mill comprising a casing having a feed opening therein, a chute adapted to be inclined in position to feed into said opening, said chute having a member fastened thereto slidably engaging the casing adjacent the feed opening whereby the chute may be adjusted to vary the size of the feed opening, and means for adjusting the inclined angularity of the chute.

5. A hammer mill comprising a casing having a feed opening therein, a chute adapted to be inclined in position to feed into said opening, said chute having a member fastened thereto slidably engaging the casing adjacent the feed opening whereby the chute may be adjusted to vary the size of the feed opening, means for adjusting the inclined angularity of the chute, and additional means carried by the chute to reduce the feeding cross sectional opening thereof so that the amount of material carried by the chute may be varied.
